TEMPERATURE-PRESERVING ARTICLE CONTAINER

Paul N. Fenske, Morton, Minn.

Application February 6, 1948, Serial No. 6,772

4 Claims. (Cl. 229—14)

1

My invention relates to temperature-preserving article containers, and more particularly to such containers as are portable and are adapted for the manual transportation of hot or cold food articles, the initial temperature of which it is desired to maintain during transportation. While it is obviously impossible to maintain the precise temperature during transportation, the device according to the invention is intended to at least retard the tendency of the article carried to assume air temperature.

With the foregoing in view, an object of my invention is to provide an improved temperature-preserving article container.

A further object is to provide an improved temperature-preserving article container which includes means spacing the article carried from all surrounding walls of the container, whereby to provide a dead air space substantially entirely around the article.

A further object is to provide a container such as that last described which includes collapsible spacing means to permit the stacking of a plurality of containers during shipment or storage.

A further object comprises a temperature-preserving article container which comprises a container made of paper or like inexpensive material which can be readily manufactured at low cost, but which is long lasting in use and capable of repeated use.

Other objects and advantages reside in the particular structure of the invention, combination and arrangement of the several parts, and will be readily understood by those skilled in the art upon reference to the attached drawing in connection with the following specification, wherein the invention is shown, described and claimed.

In the drawing:

Figure 1 is a side elevation of the container according to the invention;

Figure 2 is an end elevation thereof, parts being broken away and shown in transverse vertical section;

Figure 3 is a longitudinal vertical section taken substantially on the plane of the line 3—3 of Figure 2;

Figure 4 is a fragmentary perspective view on an enlarged scale and showing a detail of construction.

The container according to the invention may assume many forms and shapes, but in general will conform substantially to the shape of the article to be carried, particularly if the article intended to be carried is a symmetrical package. Consequently, it is to be understood that the embodiment illustrated is merely one of many forms which the container according to the invention may assume.

Referring specifically to the drawing, wherein

like reference characters have been used throughout the several views to designate like parts, 10 designates a container which is roughly of blunt wedge shape, and which is adapted to carry the conventional package of ice cream. Thus, the container according to the invention comprises side walls 11, 11 and angularly-disposed side or end walls 12, 12. The container also includes a bottom wall 13 and a conventional top closure 14 which comprises a plurality of flaps and tabs adapted to interlock in any suitable manner to provide a locked closure which may be readily unlocked for the insertion and/or removal of the article to be carried.

Inwardly of the container 10, at least a pair of opposed side walls, in this case the opposed side walls 11, 11, have mounted thereon suitable spacer members generally indicated by the reference character 16. Each of the spacer members 16 comprises a strip of paper or like readily bendable material which is formed to provide a member which is substantially flying V-shaped in cross-section. Thus, each strip 16 comprises wings 17 and 18 which merge into converging legs 19 to provide an apex or knife edge 20. Portions of the edge 20 are cut away to provide notches 21, whereby each strip comprises a plurality of longitudinally-spaced knife-edge portions 20 and interposed notches 21. The outer wings 18 are secured to the supporting side wall in any suitable manner, as by gluing or stapling, but the inner wings 17 are free, whereby the strips are foldable to lie flat along the supporting side wall.

To maintain the support members 16 in an erect article-supporting position, I have provided a check means 22 which comprises a strip of paper or like readily foldable material 22 which includes a central portion 23 which is glued, stapled, or otherwise suitably secured to a supporting side wall for the strips. The central portion 23 terminates laterally in a pair of opposed fold lines 24 and free edge flaps 25. The flaps 25 may be provided at their upper edges with tabs 26 for manipulation by the fingers of the user. As is indicated in broken lines, Figure 4, when the containers are stacked for storage or shipment, the free wing 17 of each strip 16 overlaps the check means 22, whereby each strip 16 lies substantially flat along the supporting wall and provides means for permitting the stacking of a large number of containers in a relatively small space. However, when it is desired to use the container to support an article, such as 15, each strip 16 is folded to its flying V-shape and the free wing 17 is inserted beneath the free flap 25 which is adjacent thereto of the check means 22. The engagement of the free edge of the free wing with the edge of the intermediate portion 23 50 which is secured to the supporting container wall,

maintains the strips 16 in their erect article-supporting position. The notches 21 serve the dual function of providing all-round circulation of the trapped air and also reduce the contact area of the knife edges 20 to a minimum, thus minimizing temperature changes through direct conduction through the supports and the container walls.

The bottom wall 13 of the container 10 is provided with an article-support 30 which likewise comprises a strip of foldable material, such as heavy paper, and which likewise is of flying V-shape in cross-section. The support 30 comprises wings 31 and converging legs comprising an apex or knife-edge 32, a portion or portions of which may be cut away to provide a notch or notches 33, Figure 3. The notch 33 not only minimizes the supporting engagement with the article 15, but as is the case with the notches 21, provides means permitting free circulation of air entirely around the article 15. One of the wings 31 may be secured to the bottom wall 13 and the other wing may be free, or, as shown, both wings 31 may be secured to the bottom wall. In the event that a free wing 31 is provided, it is to be understood that check means substantially similar to one-half of the check means 23 will be provided to support the support 30 in an erect article-supporting position. However, I have found that a fixed support 30 does not reduce the stacking space materially and I prefer that both wings be anchored in any suitable manner to the bottom wall 13.

While not shown in the drawing, it is to be understood that a suitable carrying handle or bail may be provided to facilitate the carrying of the container 10 from place to place. Likewise, while I have shown a container adapted to carry but a single article 15, it is to be understood that a container comprising a plurality of compartments and/or a larger number of supports 16 and 30 may be provided whereby a plurality of articles 15 may be carried in a single container.

Therefore, while I have shown and described what is now considered to be a preferred embodiment of the invention, it is to be understood that the same is susceptible of other forms and expressions. Consequently, I do not limit myself to the precise structure shown and described hereinabove, except as hereinafter claimed.

I claim:

1. Means for packing articles to preserve initial temperature conditions, comprising a container including bottom and side walls and a top closure, spacer members carried by said side and bottom walls, said members each comprising a flying V-shaped strip including wings and converging legs providing an apex, said apex being inwardly directed relative to said container, means mounting said wings on a container wall, and said apices each being forced with longitudinally-spaced notches and longitudinally-spaced knife-edge supports for supporting an article in space relation to said side and bottom walls and to said closure.

2. Means for packaging articles to preserve initial temperature conditions, comprising a container including bottom and side walls and a top closure, spacer members carried by said side and bottom walls, said members each comprising a flying V-shaped strip including wings and converging legs providing an apex, said apex being inwardly directed relative to said container, means mounting said wings on a container wall,

said apices comprising knife-edge supports for supporting an article in spaced relation to said side and bottom walls and to said closure, said strips being formed of foldable material, means fixing one wing of each strip to a container wall, the other wing of each strip being free, said strips being adapted to be flattened along said container wall for stacking, check means carried by each wall adjacent each free wing of each strip, and said free wing being movable from a flat position in overlapped relation to the adjacent check means to a position engaging said adjacent check means for maintaining said strip in an erect article-supporting position.

3. Means for packaging articles to preserve initial temperature conditions, comprising a container including bottom and side walls and a top closure, spacer members carried by said side and bottom walls, said members each comprising a flying V-shaped strip including wings and converging legs providing an apex, said apex being inwardly directed relative to said container, means mounting said wings on a container wall, said apices comprising knife-edge supports for supporting an article in spaced relation to said side and bottom walls and to said closure, said strips being formed of foldable material, means fixing one wing of each strip to a container wall, the other wing of each strip being free, said strips being adapted to be flattened along said container wall for stacking, check means carried by each wall adjacent each free wing of each strip, and said free wing being movable from a flat position in overlapped relation to the adjacent check means to an erect article-supporting position, said check means each comprising a strip of foldable material, a portion of each check means remote from the adjacent free wing being secured to a container wall to provide a free flap in juxtaposed relation to the adjacent free wing, and said adjacent free wing being adapted to be inserted beneath said flap to lock said first strip in said erect article-supporting position.

4. A temperature retaining package comprising a container including a bottom wall and side walls and a top closure, at least one foldable strip carried by each wall of said container, each strip including a side edge secured to a container wall and an opposite free side edge, each strip including a fold line intermediate said side edges and substantially parallel thereto, each strip being foldable on said fold line from a flat position lying close to a container wall to an erected position providing an inwardly directed knife-edge to supportably engage an article placed in said container, and means for releasably locking said strips in said erected positions.
